UNITED STATES PATENT OFFICE

FREDERICK HAYDEN GREEN, OF CHELTENHAM, ENGLAND

SAFETY RAZOR

Application filed October 19, 1929, Serial No. 400,909, and in Great Britain October 24, 1928.

This invention is for improvements in or relating to safety razors of the type in which a blade is adapted to be secured in shaving position or allowed to swing free for the purpose of stropping the blade.

With safety razors of the described type, the blade has generally been caused to swing periodically through approximately 180° by means of a roller in frictional or geared relation with the blade, the roller being rotated by frictional contact with a stropping surface.

The object of the present invention is to dispense with the frictional roller and to provide an improved construction of safety razor in which the blade or the holder thereof is itself, by direct engagement with the stropping surface caused to effect the necessary reversal movement of the blade during a stropping action.

According to the present invention, a safety razor comprises a single-edged razor blade, a U-shaped guard therefor lying substantially in the plane of the blade, a handle secured to the guard at approximately 45° to the plane thereof, trunnions by which the blade is mounted freely swingable in the guard about an axis parallel to and near its rear edge, shoulders along the blade at each side thereof in rear of the axis of the trunnions, a blade-locking latch pivoted to the handle to swing to and from a position in which it resiliently bears upon the shoulder at one side of the blade, a blade-adjusting set screw mounted in said latch and bearing upon the blade, at the same side thereof as the said shoulder, at a point intermediate the cutting edge of the blade and the trunnions, the said shoulders being of such depth that when the blade is released and pressed downward by the guard upon a flat stropping surface, the shoulders incline the blade at its cutting edge to an appropriate stropping angle relatively to said surface.

In order that the invention may be clearly understood reference is directed to the accompanying drawings, wherein:—

Figure 1 is a front elevation of a safety razor constructed in accordance with the invention.

Figure 2 is a sectional side elevation of Figure 1.

Figure 3 is a sectional side elevation showing a stropping element adapted for use with the improved razor, and illustrating two positions of a razor blade being stropped thereon.

Figure 4 is a section on the line 4—4 Figure 3.

Figure 5 is a similar view to Figure 3 of a modified form of stropping element illustrating two positions of a razor blade during the process of stropping and

Figure 6 is a sectional view of the stropping element provided with an outside casting, and showing a recess for the reception of the razor when not in use.

Figure 7 is a front elevation of a safety razor constructed in accordance with the invention and illustrating a construction of connecting the blade carrying guard to the handle in an adjustable manner.

Figure 8 is a sectional side elevation of Figure 7.

Referring to Figures 1 and 2, which illustrate a safety razor comprising a handle 1 connected to a U-shaped guard 2 which is arranged to project forwardly as clearly shown in Figure 2, a blade 3, is pivotally supported at 4, 5 in the U-shaped guard 2, and is maintained in the shaving position by means of a latch 6 screwed to the handle 1 by means of a screw 7, the extremity of the latch 6 bearing on the upper part of the blade 3 and preventing the same from rotating. The adjusting screw 8 is provided in order that the edge of the blade may be adjusted relatively to the base of the U-shaped guard 2.

In order that the razor blade may be stropped a stropping element 9 is provided which comprises a pair of stropping surfaces 10, 11 mounted on a rectangular box-like support 12 one side of which is left open for the reception of the safety razor when out of use. The receptacle 12 is so positioned relatively to the stropping element 9 that a pair of rectangular recesses 13, 14 are provided at each end of the said element.

The stropping surfaces 10, 11 are mounted on the receptacle 12 in such a manner as to

leave a pair of channels 15, 16 and 17, 18 respectively at each side of the said stropping surfaces. The stropping element 9 is arranged to be inserted as a slide in an open ended shell 19.

In order to strop the razor the blade is released from the shaving position by removing the latch 6 and the U-shaped guard placed on the stropping surface in such a manner that the extremities of the limbs thereof are disposed within the channels 15, 16 or 17, 18 the blade taking up a position as shown in Figure 3. By moving the safety razor in the direction of the arrow 15 Figure 3 to the position shown at the end of the said figure, the blade will be stropped, and will thereafter fall into a vertical position moving in the arc of a circle, as shown by the arrow 20. Upon the return movement of the handle that blade will be drawn over the stropping surfaces until the edge thereof is released by the end of the stropping surface and permits the blade to fall in a similar manner into the recess 13.

25 It will be appreciated that the bottom wall of the end portions of the channels 15, 16 (17, 18), that is to say, the portions of these channels which extend beyond the end of the stropping surfaces function as supporting rails for the razor after the razor has passed beyond the limits of the stropping surface in its reciprocation therewith.

35 Referring now to Figure 5 wherein the stropping surfaces 10, 11 are increased in thickness in order that the extremities of the U-shaped guard 2 are out of contact with the channels 15, 16 or 17, 18. With this construction when the blade is being stropped, the blade will when the holder is moved beyond 40 the extremity of the stropping surface be drawn forwardly and follow the path indicated by the dotted line 21, the extremities of the limbs of the U-shaped guard dropping at the end of the stropping surface so that 45 the edge of the surface contacts with the surface of the blade and jerks the same forwardly into the recess 14.

50 A similar movement takes place upon the return stropping action of the safety razor, the blade being jerked forwardly to fall into the recess 13.

55 It will be understood that the guide channels arranged on each side of the stropping surface act as guides permitting the blade to receive pressure, and the extensions of the channels on the well portions support the U-guard at the finish of the stropping movement.

60 Instead of causing the blade to drop into the two wells to effect the reversal of the blade, the guide channels may be arranged so that the ends of the arms of the guard at the end of their travel in one direction drop 65 so as to cause the blade to strike the end of

the stropping surface and swing upwardly, over into the reverse position.

Referring now to Figures 7 and 8 which show a construction in which the U-shaped guard 2 is adjustably mounted on the handle 1. 70

In this construction the U-shaped guard 2 is connected to the handle 1 by means of a knuckle joint comprising a female member 22 and a male member 23, pivotally connected together by means of a pivot 24. 75

The male member 23 is provided with a screw-threaded stem 25 which is engaged with the handle 1, the said handle 1 being provided with a cup-shaped end 26 which co-acts with the curved extremities 27 provided 80 in the female member 22.

The male member 23 is provided with a screw-threaded stem 25 which is engaged with the handle 1, the said handle 1 being provided with a cup-shaped end 26 which co-acts with the curved extremities 27 provided 85 in the female member 22.

I claim:

A safety razor, comprising a single-edged razor blade, a U-shaped guard therefor lying substantially in the plane of the blade, a handle secured to the guard at approximately 90 45° to the plane thereof, trunnions by which the blade is mounted freely swingable in the guard about an axis parallel to and near its rear edge, shoulders along the blade at each side thereof in rear of the axis of the trunnions, a blade-locking latch pivoted to the handle to swing to and from a position in which it resiliently bears upon the shoulder at one side of the blade, a blade-adjusting set screw mounted in said latch and bearing upon the blade, at the same side thereof as the said shoulder, at a point intermediate the cutting edge of the blade and the trunnions, the said shoulders being of such depth that when the blade is released and pressed downward by the guard upon a flat stropping surface, the shoulders incline the blade at its cutting edge to an appropriate stropping angle relatively to said surface. 95 100 105 110 115
